(57) CLAIM

The ornamental design for a gym bench towel, as shown and described.

DESCRIPTION

FIG. 1 is a perspective view of the gym bench towel showing my new design;

FIG. 2 is a left side view thereof;

FIG. 3 is a right side view thereof;

FIG. 4 is a bottom view thereof;

FIG. 5 is a top view thereof;

FIG. 6 is a front end view thereof;

FIG. 7 is a rear end view thereof;

FIG. 8 is a perspective front view showing the gym bench towel positioned on the front surface of a bench seat back shown in phantom lines; and,

FIG. 9 is a perspective rear view of the gym bench towel of FIG. 8 positioned on the rear surface of a bench seat back shown in phantom lines.

The broken lines illustration of unclaimed portions of the gym bench forms no part of the claimed design.
